United States Patent Office

Des. 225,686
Patented Dec. 26, 1972

225,686

JUKEBOX OR SIMILAR ARTICLE

Horst Friedrich, Bad Kreuznach, Germany, assignor to
NSM-Apparatebau G.m.b.H., Kommanditgesellschaft,
Bingen, Germany

Filed Nov. 8, 1971, Ser. No. 196,877

Term of patent 14 years

Int. Cl. D14—01

U.S. Cl. D56—4

Fig. 1

Fig. 2

FIG. 1 is a left side elevational view of a jukebox or similar article, showing my new design, the opposite side being substantially a mirror image thereof; and

FIG. 2 is a left side, top and front perspective view thereof.

The back, not shown, is substantially unornamented.

Portions of the drawing figures are diagonally lined to indicate transparency.

I claim:

The ornamental design for a jukebox or similar article, as shown and described.
